CLAIM

I claim the ornamental design for a lighter holder with knife and clip, as shown and described.

DESCRIPTION

FIG. 1 is a front, right, top perspective view of a lighter holder with knife and clip in a closed configuration;

FIG. 2 is a top plan view of the lighter holder with knife and clip thereof;

FIG. 3 is a bottom elevation view of the lighter holder with knife and clip thereof;

FIG. 4 is a right-side elevation view of the lighter holder with knife and clip thereof;

FIG. 5 is a left side elevation view of the lighter holder with knife and clip thereof;

FIG. 6 is a top plan view of the lighter holder with knife and clip of thereof;

FIG. 7 is a bottom elevation view of the lighter holder with knife and clip of thereof;

FIG. 8 is a front, right, top perspective view of a lighter holder with knife and clip in a closed configuration according to another aspect of the present invention;

FIG. 9 is a top plan view of the lighter holder with knife and clip thereof;

FIG. 10 is a bottom elevation view of the lighter holder with knife and clip thereof;

FIG. 11 is a right-side elevation view of the lighter holder with knife and clip thereof;

FIG. 12 is a left side elevation view of the lighter holder with knife and clip thereof;

FIG. 13 is a top plan view of the lighter holder with knife and clip of thereof; and,

FIG. 14 is a bottom elevation view of the lighter holder with knife and clip of thereof.

The broken lines show features of the lighter holder with knife and clip that form no part of the claimed design.
